RESILIENT HINGE MOUNTING

Richard F. Timken and Spencer Jones,
Palo Alto, Calif.

Application September 25, 1952, Serial No. 311,474

9 Claims. (Cl. 16—128)

1

This invention relates to a new and improved resilient hinge mounting such as may be employed to hingedly support sewing machines or like mechanisms.

The particular embodiment of the invention illustrated in the drawings, and which will be described hereinafter in greater detail, comprises, generally, a shock absorbing cushion formed of resilient material defining top, bottom, and side surfaces, and a hinge mechanism comprising first and second hinge leaves pivotally connected to one another by a hinge pin. The first hinge leaf comprises a relatively flat plate which is preferably adhesively mounted on the cushion parallel to, and adjacent the top surface of, said cushion. The novel arrangement and construction of the parts, to be described hereinafter in more detail, is such that the weight of the object, such as a sewing machine, supported by the hinge mechanism is equally distributed to the areas of the cushion located on opposite sides of the hinge pin, thereby insuring maximum shock absorbing efficiency of the resilient cushion material.

It is a principal object of the present invention to provide a resilient shock absorbent hinge mounting particularly adapted for supporting sewing machines or like mechanisms to a primary support such as a table or stand, and in such manner as to absorb a substantial quantity of machine vibration without permitting its transmittal to said primary support.

Another object and advantage of the invention is to provide a resilient hinge mounting of the character briefly mentioned above which will permit the sewing machine or other object supported thereby to be swung downwardly below the table or stand surface in an out-of-the-way position when not in use.

Other numerous objects and advantages of the present invention will become apparent upon reading the following specification and referring to the accompanying drawings in which similar characters of reference represent corresponding parts in each of the several views.

In the drawings:

Fig. 1 is a perspective view of a preferred embodiment of the hinge mounting.

Fig. 2 is a top plan view of the same.

Fig. 3 is a sectional view taken on line 3—3 of Fig. 2.

Fig. 4 is a sectional view taken on line 4—4 of Fig. 2.

Fig. 5 is a sectional view taken on line 5—5 of Fig. 1.

Fig. 6 is a vertical sectional view showing how

the hinge mounting may be employed to support a sewing machine in a down out-of-the-way position.

Fig. 7 is the same as Fig. 6 showing the sewing machine supported above the table surface.

Fig. 8 is a fragmentary plan view of a sewing machine supported to a table by a pair of hinge mountings constructed in accordance with the invention.

10 Referring now more particularly to the drawings, the resilient hinge mounting therein disclosed comprises, generally, a shock absorbing cushion A, a hinge mechanism B, and an anchoring plate C. For purposes of convenient illustration and explanation, the side of the mounting designated generally at D may be considered as the front side of the mounting and the side designated generally at E as the back or rear portion of the mounting.

15 20 The shock absorbing cushion, heretofore designated generally at A, comprises, more specifically, a block of resilient shock absorbing material such as rubber, which, in the embodiment shown, is substantially circular in cross-section and generally truncated-conical shape in side elevation, defining parallel top and bottom surfaces 11 and 12, respectively, and side surfaces 13. The bottom perimeter of the block is shown as being slightly larger than the top perimeter of the block

25 30 to facilitate its insertion within a circular cut-out formed in a primary support such as a table surface from the underside thereof, as explained more fully hereinafter.

35 40 A circular recess or well, indicated at 14, is formed in the top of the block concentrically with the top circumference of the block, and is shaped and proportioned to snugly accommodate hinge leaf 16 of the hinge mechanism, heretofore designated generally at B.

45 50 Hinge leaf 16, in turn, comprises a relatively flat circular plate formed with an elongate slot 17 extending from the outer edge of the plate inwardly toward and substantially beyond the center point of said plate. Plate 16 is preferably adhesively cemented or vulcanized, as at 18, to the cushioning material within recess 14.

Hinge leaf 19 of hinge mechanism B comprises an elongate rod-like member which is shown as being formed with an abutment shoulder 21, and a circumferential key-way 22 adjacent its outer extremities.

The base of hinge leaf 19 is pivotally connected to leaf 16 by means of hinge pin 23 which extends transversely of slot 17 and through leaf 55 19. In this connection it is noted that slot 17

is of sufficient size to accommodate and permit free and unobstructed movement of hinge leaf 19 rotatably about pin 23. Moreover, and as will hereinafter be explained more fully, similarly proportioned slots are also formed in the cushioning material and anchor plate in vertical registry with slot 17 for permitting desired movement of hinge leaf 19 about its pivotal axis.

In the preferred embodiment of the invention, and with particular reference to Fig. 2 of the drawings, the device is constructed so that the total cushion supported area of the hinge leaf plate 16 located on one side of the hinge pin substantially equals the total cushion supported area of the plate 16 located on the opposite side of the hinge pin. More specifically, it is observed that the hinge pin 23 is disposed along a chord line of the circular plate 16 extending at right angles to the axis of slot 17 and located somewhat rearwardly of the center line of the circular plate. The arrangement is such, therefore, that the cushion supported area 26 of the plate located to the rearward side of hinge pin 23 substantially equals the cushion supported areas 27 and 28 of the plate located to the frontward side of the hinge pin 23. Thus, weight of the hinge supported mechanism, such as a sewing machine, transmitted through hinge leaf 19 via hinge pin 23, will be distributed evenly to the cushion material located on either side of the hinge pin. In this respect it is pointed out that if the rearward cushion supported area 26 was either substantially less or substantially greater than the combined front cushion supported areas 27 and 28 of plate 16, the weight of the supported mechanism transmitted to the hinge pin would tend to tilt the plate one way or the other and cause uneven stress and compressive forces to be transmitted to the cushion material. Such a condition, in turn, would decrease the efficiency of the cushion material to absorb vibration from the supported sewing machine or other mechanism during operation thereof.

The anchoring plate, heretofore designated generally at C, is preferably adhesively mounted, as at 29, to the underside of the cushion in such manner that its opposite ends extend outwardly to either side of said cushion. Screw or bolt holes, such as indicated at 31, may be formed through the anchoring plate to permit the hinge mounting unit to be rigidly affixed to the underside of a sewing machine table or similar primary support.

As hereinabove suggested, suitable slots, indicated at 17a and 17b are formed in both the cushion A and anchoring plate C. These slots are of the same size as, and are in registry with, slot 17 formed in hinge plate 16 so as to permit free and unobstructed pivotal movement of hinge leaf 19 through at least 90° from a first position whereas said hinge leaf extends outwardly in a direction parallel to the plane of plate 16 (as shown in full lines in Fig. 1 and in broken lines in Figs. 2 and 4), downwardly to a second position whereat said hinge leaf 19 depends perpendicular to the plane of plate 16 (as shown in full lines in Figs. 2, 3, and 4).

It is further noted that the total cushion supporting area 32 of the anchoring plate located to the rearward side of the vertical plane of the hinge pin axis 23 substantially equals the combined or total areas 33 and 34 of the cushion supporting areas of the anchoring plate located to the frontward side of the vertical plane of the hinge pin axis. The reason for this preferred

arrangement is, as above explained, to prevent unequal stress or compressive forces being imparted to the cushion supporting material through weight of the object supported.

5 Figs. 6 and 7 show a more or less conventional sewing machine table or stand 30 in which the sewing machine, indicated at 35, is adapted to be hingedly supported within a conventional slot or opening 30a formed in the table top in order that the machine may be swung from a "down" and out-of-the-way position below the table surface (such as shown in Fig. 6) to an "up" and ready-for-use position (such as shown in Fig. 7).

10 15 Fig. 8 discloses how a pair of the present hinge mountings may be secured to the wood table support 36 of a conventional sewing machine table 30 by forming therein cut-outs, such as indicated at 37, each of which are proportioned to 20 snugly receive the block of cushioning material A. The cushion may be inserted into the cut-outs from the underside of the table support and the device rigidly secured in position by screwing or bolting anchoring plate C to the under- 25 side of the table support, such as shown in Fig. 3.

It is understood that the construction of the supporting stand or table per se does not constitute a part of the present invention—such constructions being conventional and well known in 30 the art.

It has become more or less standard practice to hingedly support sewing machines to tables or stands of the type indicated at 30, usually by two hinges secured to the base of the machine 35 adjacent opposite ends thereof.

Many conventional sewing machines are provided with hinge receiving recesses or wells, such as indicated at 38, which are adapted to receive and clamp, as by set screws indicated at 39, hinge 40 leaves of the general shape and size of leaf 19. In this regard it is seen that abutment shoulder 21 of hinge leaf 19 abuts against the end of recess 38, and key-way 22 is adapted to receive and be 45 securely engaged by set screw 39. As above noted, it is an object and advantage of the invention to provide a novel resilient mounting capable of adaptation to, and utilization with respect to, more-or-less conventional sewing machines and related accessories, such as conventional sewing machine tables and stands.

50 Although the present invention has been described in some detail by way of illustration and example for purposes of clarity of understanding, it is understood that certain changes and modifications may be made within the spirit of the invention as limited only by the scope of the claims appended hereto.

We claim:

1. A resilient hinge mounting comprising; a 60 shock absorbent cushion formed of resilient material defining top, bottom, and side surfaces, a first hinge leaf comprising a relatively flat plate mounted on said cushion adjacent and parallel to the plane of the top surface of said cushion, 65 a slot formed in said first hinge leaf extending inwardly from a marginal edge thereof, a second hinge leaf pivotally connected to said first hinge leaf within said slot by a hinge pin extending transversely across said slot, a slot formed 70 through said cushion extending from the top to bottom surfaces and inwardly from one side of said cushion in registry with said slot in said first hinge leaf to accommodate pivotal movement of said second hinge leaf from a first position dis- 75 posed substantially parallel to the top surface of

said cushion downwardly to a second position disposed substantially perpendicular to the top surface of said cushion.

2. A resilient hinge mounting according to claim 1 and wherein an anchoring plate formed with a slot in registry with said registering slots in said first hinge leaf and said cushion is mounted to said cushion adjacent the bottom surface of said cushion.

3. A resilient hinge mounting according to claim 1 and wherein the total cushion supported areas of the said first hinge leaf plate located on one side of said hinge pin approximately equals the total cushion supported areas of said plate located on the other side of said hinge pin.

4. A resilient hinge mounting according to claim 1 and wherein an anchoring plate formed with a slot in registry with said registering slots in said first hinge leaf and said cushion is mounted to the bottom surface of said cushion for supporting said cushion, and wherein the total cushion supporting areas of the anchoring plate located to one side of the vertical plane of the hinge pin substantially equal the total cushion supporting areas of the anchoring plate located on the other side of the vertical plane of said hinge pin.

5. A resilient hinge mounting comprising; a shock absorbent cushion formed of resilient material defining top, bottom, and side surfaces; a first hinge leaf comprising a relatively flat plate mounted on and supported by said cushion parallel to the plane of, and adjacent the top surface of, said cushion; said hinge leaf formed with a first slot extending inwardly from a marginal edge of said first leaf; a second hinge leaf connected pivotally to said first hinge leaf within said slot by a hinge pin extending transversely of said slot; a slot formed in said cushion in registry with said slot in said first hinge leaf proportioned to accommodate pivotal movement of said second hinge plate and extending from the top to bottom surfaces and inwardly from one side of said cushion; said above recited slots defining an open passage for pivotal movement of said second hinge leaf through at least 90° from a first position extending outwardly substantially parallel to the top surface of said cushion downwardly through said slots to a second position disposed substantially perpendicular to the top surface of said cushion.

6. A resilient hinge mounting according to claim 5 and wherein an anchoring plate disposed substantially parallel to said first hinge leaf plate is secured to the bottom surfaces of said cushion; and wherein a slot is formed in said anchoring plate in registry with said registering slots in said first hinge leaf and said cushion.

7. A resilient hinge mounting according to claim 5 and wherein the total cushion-supported areas of the said first hinge leaf plate located on one side of said hinge pin approximately equal the total cushion-supported areas of said plate located on the other side of said hinge pin.

8. A resilient hinge mounting comprising; a shock absorbent cushion formed of resilient material defining top, bottom, and side surfaces; a first hinge leaf comprising a relatively flat plate mounted on and supported by said cushion parallel to the plane of, and adjacent to the top surface, of said cushion; a slot formed in said first hinge leaf extending inwardly from a marginal edge of said first leaf; a second hinge leaf connected pivotally to said first hinge leaf in said slot by a hinge pin extending transversely of said slot; a slot formed in said cushion in vertical registry with said slot in said first hinge leaf proportioned to accommodate pivotal movement of said second hinge plate and extending from the top to bottom surfaces and inwardly from one side of said cushion; an anchoring plate secured to and supporting the bottom surface of said cushion and disposed in parallel relationship to said first hinge leaf plate, a slot formed in said anchoring plate in vertical registry with said registering slots in said first hinge leaf and said cushion proportioned to accommodate pivotal movement of said second hinge leaf; said three above recited slots defining an open passage for pivotal movement of said second hinge leaf through at least 90° from a first position extending outwardly and parallel to the top surface of said cushion downward through said slots to a second position disposed substantially perpendicular to the top surface of said cushion; the total cushion-supported areas of said first hinge leaf plate disposed on one side of said hinge pin being substantially equal to the total cushion-supported areas of said plate disposed on the other side of said hinge pin.

9. A resilient hinge mounting according to claim 8 and wherein the total cushion-supporting areas of the anchoring plate located to one side of the vertical plane of the hinge pin substantially equal the total cushion-supporting areas of the anchoring plate located on the other side of the vertical plane of said hinge pin.
